United States Patent Office.

SAMUEL KEEN, OF EAST BRIDGEWATER, MASSACHUSETTS.

Letters Patent No. 96,120, dated October 26, 1869.

IMPROVED HEEL-CUTTING MACHINE.

The Schedule referred to in these Letters Patent and making part of the same.

To all whom it may concern:

Be it known that I, SAMUEL KEEN, of East Bridgewater, in the county of Plymouth, and State of Massachusetts, have invented certain new and useful Improvements in Heel-Cutting Machines; and I do hereby declare that the following is a full and exact description thereof, reference being had to the accompanying drawings, and to the letters of reference marked thereon.

The nature of my invention consists—

First, in giving to the knife of a heel-cutting machine a motion tangential to the heel-pattern or guard, so that it will cut naturally on the tangent line.

Second, in certain mechanical devices, which can only be understood by reference to the drawings and specification.

To enable others skilled in the art to make and use my invention, I will proceed to describe its construction and use.

Drawings.

Figure 1 represents a perspective view of my machine.

Figure 2 is an elevation, the shoe-holding part L¹ (fig. 1) being removed, to show the other part more clearly.

Figure 3 shows the knife and handle.

Figure 4 is a section of the knife.

I construct my machine as follows:

A B represent the base and standard, to which the other parts of the machine are attached.

C is a shaft or spindle, supported by the standard B, and operated by the hand-lever C'.

To the shaft C, the cam D, the head-piece L of the jacking-device L¹ L², and the heel-pattern or guard P, are attached, and are severally removable.

The cam D, the shape of which is more clearly indicated in fig. 2, operating upon the projection D³ of the lever D', fig. 2, acting through the lever D¹, link D², lever E, and knife-socket H, causes the knife H' to move up and down; that is, tangentially to the heel-pattern P.

As this tangential motion of the knife, caused by the cam D, is the essential feature of my invention, I wish to call especial attention to it.

If the heel-pattern P were round, there would be no need of this tangential motion of the knife H, for then the knife might be set in position, and it would cut perfectly well, but as the pattern P is not round, it is evident that if the knife is set so as to be tangent to one part, as, for instance, the point p, fig. 2, it would not be tangent to the point p', when that has revolved so as to come in contact with the edge of the knife.

By my device the knife moving tangentially up and down, as the case may be, at the same time it is being revolved, the resultant of these two motions will, if the cam D is arranged properly, be a line always tangent to the pattern; in other words, the knife will always cut at the best advantage.

M M' is a screw, by means of which the shoe is held in position.

P', on the pattern P, serves as a guide and support for the front edge of the heel.

N' is a small roller, hung eccentrically upon the bar N, and serves as a rest, to hold the toe of the shoe.

N' being eccentric, by turning it, it can be made to suit the different style and sizes of boots and shoes.

The handle K of the knife H is made cam-shape, as shown at K², figs. 2 and 3.

This cam-form part rests against the guide K¹, so that when it is desired to change the lateral position of the knife, to suit heels of different thicknesses, it may be turned so as to bring different parts to rest against the guide K¹.

H², figs. 3 and 4, is a lip, the upper end of which is sharpened.

This lip runs between the sole and upper, and serves as a guide to the knife, and at the same time cuts off the feather-edge.

S is a spring, which serves to keep the knife in proper position.

When this machine is in use, the operator controls the motion of the knife somewhat by the handle K, by means of which the style of the heel may be varied.

The lever E, to which the knife-socket H is attached, by means of the pin R, is provided with a number of holes, r, r', &c., so that the position of the knife may be changed to suit different-sized heels.

What I claim as my invention, and desire to secure by Letters Patent of the United States, is—

1. The reciprocating knife H', operated by the cam D, or its equivalent, substantially as described, and for the purpose set forth.

2. The combination and arrangement of the cam K², the knife H', and the guard K¹, substantially as described, and for the purpose set forth.

3. The combination of the adjusting-cam N' with the jacking-device L L¹ L², substantially as described, and for the purpose set forth.

SAMUEL KEEN.
